Primary Examiner — Eric L Goodman*Assistant Examiner* — Darcey E Heflin(74) *Attorney, Agent, or Firm* — Tucker Ellis LLP; Carlos Garritano(57) **CLAIM**

The ornamental design for a funnel for bottle cap, as shown and described.

DESCRIPTION

FIG. 1 is a top front perspective view of a funnel for bottle cap showing our new design;

FIG. 2 is a front view of the funnel illustrated in FIG. 1;

FIG. 3 is rear view of the funnel illustrated in FIG. 1;

FIG. 4 is a top view of the funnel illustrated in FIG. 1;

FIG. 5 is a bottom view of the funnel illustrated in FIG. 1;

FIG. 6 is a left side view of the funnel illustrated in FIG. 1; and

FIG. 7 is a right side view of the funnel illustrated in FIG. 1; and,

FIG. 8 is a cross-sectional view of the funnel for a bottle cap illustrated in FIG. 4.

1 Claim, 5 Drawing Sheets(56)
